B. F. GREER

SAVINGS BANK

Filed Nov. 25, 1924

FIG. 1.

FIG. 2.

FIG. 4.

FIG. 5.

INVENTOR
BUTLER F. GREER
White Post & Goran
by
HIS ATTORNEY.

Patented Apr. 12, 1927.

UNITED STATES PATENT OFFICE.

BUTLER F. GREER, OF SAN FRANCISCO, CALIFORNIA.

SAVINGS BANK.

Application filed November 25, 1924. Serial No. 752,113.

My invention relates to a small portable money bank comprising a lock box or receptacle provided with slots thru which the coins are introduced.

5 One of the objects of the invention is the provision of a bank of this kind having a plurality of coin receiving receptacles with means for rendering visible the amount in each of the receptacles. Another object of 10 the invention is the provision of a money safe or bank of the character described of sturdy construction which at the same time is economical to make. Another object of the invention is the provision of a bank comprising readily assembling units of such character as to be easily and cheaply formed by dies from sheet metal. Another object 15 of the invention is the provision of a bank, which when opened presents the coins there- 20 in in orderly arrangement, so that they may be lifted out and stacked without sorting and undue handling.

My invention possesses other objects which with the foregoing will be set forth 25 in the following description of the preferred embodiment of means for practicing the invention which is illustrated in the drawings accompanying and forming part of the specification. It is to be understood 30 that I do not limit myself to the showing made by the said description and drawings as I may adopt variations of my preferred form within the scope of my invention as set forth in the claims.

35 Referring to the drawings:

Figure 1 is a plan view of one side of my bank.

Figure 2 is a sectional view, the plane of section being indicated by the line 2-2 of

40 Figure 1.

Figure 3 is a perspective view of the open bank, showing coins in each compartment.

Figure 4 is a detail of the money slot guard in perspective.

45 In broadly descriptive terms the bank of my invention comprises a rectangular casing in two equal parts hinged together. In each half of the casing is a corrugated sheet which provides grooves and when the two 50 halves or lids of the casing are closed, the grooves combine to form separate coin receptacles. A coin admission slot is formed in the casing for each receptacle so formed, and a line of closely spaced apertures opposite each receptacle in the wall of the casing 55 permits the contents of each receptacle to be

noted without opening the casing. A bill compartment is provided in one end of the casing, and is formed by channel shaped members, which also function to hold the 60 corrugated sheets in place. The various constructional units of my bank are preferably formed by dies from a suitable gauge of sheet metal and because of the improved method of forming the parts and their inter- 65 relation, the bank is readily assembled and may be produced at a relatively small cost.

More particularly my bank comprises a two-part casing composed of the lids 2 and 3, each lid comprising a shallow open top 70 rectangular box. The lids are pivotally connected by a hinge 4, and a lock operated by the key 6 is provided at the opposite end so that the parts may be secured together 75 in the closed position.

Arranged in one of the lids 2 is a corrugated sheet designated as a whole by the reference character 7, and so bent as to provide three grooves 8, 9 and 10, as shown in Fig. 3. Preferably these grooves are of 80 such size approximately as the half of a quarter, nickel and dime respectively. The corrugated sheet at the hinged end is secured in place by the lug plate 12, flanged at the edges to fit snugly into the hinged end 85 of the lid, and provided with tongues 13, stamped from the body of the plate, at such intervals as to provide the required support for the corrugated sheet.

At the opposite end, the corrugated sheet 90 is supported by the plate 14, formed with inwardly turned tabs 15 so placed as to engage under the edge of the corrugated sheet at appropriate intervals. Studs 16 95 pressed from the plate 14 and engaging over the ends of the sheet hold it in place.

It is to be noted that the flanged edges 17 of the corrugated sheet are flush with the edges of the lid in which it lies. The plate 14 forms one side of a channel which may 100 be used as a note or bill container, the bottom 18 of which is suitably secured to the wall of the case, and the other side 19 of which is provided with a flange 21, adapted to meet the end wall of the casing and provide a recess 22 in which suitable lock mechanism 23 may be conveniently placed. An aperture 20 in the lid 2 opens into the channel to permit notes or bills to be inserted 105 thereinto when the box is closed.

The other lid 3 is also provided with a corrugated sheet 24 formed to provide

grooves 26, 27 and 28, which combine with the grooves 8, 9 and 10 respectively, to form coin receptacles. Coins may be introduced into these separate receptacles when the lids 5 are closed, thru the slots 29, each of which is guarded by an arm 31, resiliently pressed by the spring 32 into position over the slot. The arms 31 are pivotally mounted in a plate 33, seated in the end of the casing in 10 the same manner as the lug plate 12.

To provide an opportunity for a coin inserted thru one of the slots, to fall into the receptacle formed by the combined grooves, the corrugated sheet 24 is cut away as shown 15 in Fig. 3, adjacent the coin slots, leaving extending arms 34, seating under the flanged edge 36 of the plate 33. The opposite end of this corrugated sheet is retained in position by short studs 37 driven out on the plate 38, which corresponds to and overlies the plate 14, when the lids are closed. It 20 will be noted that the plate 38 projects beyond the edges of the lid in which it lies, so as to interlock between the sides of the opposite lid. This is done to give increased 25 stability to the closed bank, and prevent the racking of the connected halves. The plate 38, like the plate 14, comprises one side of a channel member rigidly secured in the end 30 of the casing and having the other side 39, provided with the flange 41, forming with the adjacent end of the box, a recess 42 in which the latches or bolts 43 of the lock 35 may engage.

Formed in the bottom of each groove in the sheet 24 and extending thru the contiguous wall of the casing, are lines of closely spaced apertures 44, thru which the 40 coins in the bank may be viewed. Preferably numbers 46 are etched or stamped in the outer surface adjacent the apertures, so that the value of the accumulated coins within the bank may be noted by reading the number opposite the top of the stack.

It will be noted that when my bank is open, the coins therein are already segregated, and lie in such position as shown in Fig. 3, that they may be readily removed and stacked without sorting or separate handling.

I claim:

1. A savings-bank comprising two lids hinged together, each lid comprising a sheet having flanged edges which abut to form the sides of the savings-bank, and a channel having its bottom member secured to one of the sides of the savings-bank, and a channel 55 having its bottom member secured to one of the side members of the channel forming with the flanged edge of the lid a casing for lock mechanism, and the other side member of the channel extending beyond the edge of the lid to interlock between the sides of the other lid when the lids are closed.

2. A savings-bank comprising two lids

hinged together, a corrugated sheet forming grooves in each lid and which combine to form separate coin receptacles when the lids are closed, and a channel having its bottom member secured to one of the lids opposite 70 the hinged edge, one of the side members of the channel forming with the lid edge a casing for lock mechanism, and the other side member of the channel closing the ends of the grooves in the corrugated sheet. 75

3. A savings-bank comprising two lids hinged together, a corrugated sheet forming grooves in each lid and which combine to form separate coin receptacles when the lids are closed, and a channel having its bottom member secured to one of the lids opposite 80 the hinged edge, one of the side members of the channel having an outwardly turned flange abutting against the edge of the lid to form a casing for lock mechanism, and the other side member of the channel closing the ends of the grooves in the corrugated sheet. 85

4. A savings-bank comprising two lids hinged together, a corrugated sheet forming 90 grooves in each lid and which combine to form separate coin receptacles when the lids are closed, and a channel in each lid opposite the hinged edge, one of the side members of each channel forming with the adjacent 95 lid edge a casing for lock mechanism, and the other side member of each channel closing the ends of the grooves in the adjacent corrugated sheet. 100

5. A savings-bank comprising two lids hinged together, a corrugated sheet forming 105 grooves in each lid and which combine to form separate coin receptacles when the lids are closed, and a channel in each lid opposite the hinged edge and which combine to form a bill receptacle when the lids are closed, one of the side members of each channel forming with the adjacent lid edge a 110 casing for lock mechanism, and the other side member of each channel closing the ends of the grooves in the adjacent corrugated sheet. 110

6. A savings-bank comprising two lids hinged together, a corrugated sheet forming 115 grooves in each lid and which combine to form separate coin receptacles when the lids are closed, and a channel in each lid opposite the hinged edge and which combine to form a bill receptacle when the lids are 120 closed, one of the side members of each channel forming with the adjacent lid edge a casing for lock mechanism, and the other side member of each channel closing the ends of the grooves in the adjacent corrugated sheet, one of the last named side members extending beyond the edges of the lid to 125 interlock between the sides of the other lid. 125

7. A savings-bank comprising two lids hinged together, a corrugated sheet forming 130

grooves in each lid and which combine to form separate coin receptacles when the lids are closed, and a channel in each lid opposite the hinged edge and which combine to form a bill receptacle when the lids are closed, one of the side members of each channel forming with the adjacent lid edge a casing for lock mechanism, and the other

side member of each channel closing the ends of the grooves in the adjacent corrugated sheet, the lids being provided with apertures for the admission of coins to the coin receptacles and bills to the bill receptacle.

In testimony whereof, I have hereunto set my hand.

BUTLER F. GREER.
